UNITED STATES PATENT OFFICE.

HUGH D. FORTNER, OF EL RENO, OKLAHOMA.

FOLDABLE TUB-STAND AND WRINGER-SUPPORT.

1,134,836.

Specification of Letters Patent.

Patented Apr. 6, 1915.

Application filed November 13, 1912. Serial No. 731,132.

To all whom it may concern:

Be it known that I, HUGH D. FORTNER, a citizen of the United States, residing at El Reno, in the county of Canadian and State 5 of Oklahoma, have invented new and useful Improvements in Foldable Tub-Stands and Wringer-Supports, of which the following is a specification.

The present invention relates to a foldable 10 tub stand and wringer support, and the object of the invention is to produce a structure which may be easily and quickly converted into any of the above mentioned devices and further to provide a structure with 15 simple but effective means whereby the same, when set up to form a device, shall embody strength and rigidity.

A further object of the invention is the provision of a device of this character which 20 shall be simple in construction, cheap to manufacture and thoroughly effective in use.

With the above recited objects in view and others which will appear as the nature of the invention is more fully disclosed, the 25 improvement resides in the construction, combination and arrangement of parts set forth in the following description and falling within the scope of the appended claims.

In the drawings accompanying this specification and forming a part thereof: Figure 1 is a view of my device in its collapsed or folded position. Fig. 2 is a perspective view of the same when set up to provide a step ladder. Fig. 3 is a similar view showing the device arranged to provide an ironing board and clothes rack. Fig. 4 is a similar view illustrating the device set up to provide a tub stand and wringer support. Fig. 5 is a central longitudinal sectional view taken through device illustrated in Fig. 4. Fig. 6 is a detail sectional view taken approximately upon line 6—6 of Fig. 2. Fig. 7 is a horizontal sectional view upon the line 7—7 of Fig. 2. Fig. 8 is a central longitudinal sectional view taken approximately upon line 8—8 of Fig. 3. Fig. 9 is a similar sectional view upon line 9—9 of Fig. 3. Fig. 10 is a detail perspective view of the wringer support and 50 drain board. Fig. 11 is a sectional view upon line 1—1 of Fig. 3. Fig. 12 is a detail sectional view approximately upon line 12—12 of Fig. 4.

Referring now to the drawings in detail, 55 the numeral 1 designates a member 1, when

the device is shown in the position illustrated in Fig. 3 of the drawings comprising the ironing board. The board 1 is of usual shape, but has its sides as well as its rounded front formed with a continuous groove or depression 2. The rear end of the board preferably has its edges inclined toward its sides, and has secured upon the said edges eyes 3. Arranged within the groove is a flexible element 4 which has its ends provided with threaded members 5 which project through the eyes 3 which have their outer extremities provided with adjustable elements in the form of thumb nuts 6. By this arrangement it will be noted that the element 4 provides a means whereby the covering of padding for the board may be easily and quickly arranged thereon and sustained against accidental displacement. Furthermore, the construction provides for a ready removal of the covering or padding when the same becomes worn and is to be replaced. The board adjacent its rear end has one of its faces provided with a transversely arranged strip 7, the same being in the nature of a rectangular member and having its opposite ends formed with trunnions the purpose of which will presently be set forth. The strip 7 is centrally formed with a substantially rectangular opening 9 that is arranged to communicate with the board 1. This face of the board, directly forward of the said opening and strip is provided with one or more studs 10.

The numeral 11 designates the sleeve board for the device. The board proper is of the ordinary formation and has its under face adjacent its rear portion provided with a substantially T-shaped element 12 including a longitudinally extending strip 13 and a transversely arranged strip 14. The said T-shaped element rests upon the upper face of the board 1, and means are employed for preventing any accidental displacement of the sleeve board 11 from the ironing board 1, and including a catch member designated by the reference character 15. The said catch member embodies a substantially L-shaped flat spring having one end secured in any suitable manner to the sleeve board and thence extended downwardly and forwardly through the opening 9 of the strip 7, and the opening 17 formed in said spring adjacent the free terminal thereof is engaged with the stud 10. The 100 105 110

free terminal of the spring is inclined downwardly and forwardly to provide the catch member with a manipulating portion 16.

The under face of the ironing board is 5 provided with oppositely arranged sliding bolts 18; with a set of cleats 19 arranged transversely of the board and which have one of their faces inclined or beveled; with a hook 20, and with a hook 21, the purpose 10 of all of these elements will be later fully set forth.

The numeral 22 designates the member 15 which provides a step ladder when the device is in the position illustrated in Fig. 2 of the drawings. The ladder comprises the usual spaced sides as well as the connecting steps, and the side members of the ladder are provided with suitable openings within 20 which are received the trunnions 8 of the strip 7, and whereby the said ladder is horizontally connected with the ironing board 1.

Passing through the side rails of the ladder adjacent its pivotal connection with the 25 trunnions 8 is a rod 23. This rod may have one or both of its ends threaded, and the said threaded ends engaged by thumb nuts 24. The projecting ends of the rod 23 are 30 adapted to pass through the elongated openings 25 provided in the side arms 26 of what I will term a shelf member 27. The member 27 is provided with a plurality of spaced transversely arranged connecting 35 strips 28, and pivotally secured between these strips are clothes supporting arms 29. These arms are adapted to fully fill the spaces between the strips 28 and when said arms are in the position illustrated in Fig. 3 of the drawings they are sustained horizontally 40 of the member 27 through the medium of one of the side arms 26 with which said strips contact. The strips are each provided upon their under face with a turn button 30 which is adapted to engage the under face of the strips 28 adjacent each of 45 the arms 29.

The outer connecting member 31 for the side arms is trunnioned to the said arms and is centrally provided with a round opening 50 32 which is intersected by a slit or depression 33 which is arranged longitudinally of one of the faces of the member 31. The member 31 is substantially square in cross section and pivotally secured within the slit 55 21 is a locking element 34 (see Fig. 2). This element 34 is in the form of a strip of flat metal which has its upper edge bent at an angle to provide a finger hole 35. The numeral 36 designates a rod which is adapted 60 to pass through the opening 32 when the device is in the position illustrated in Fig. 3 of the drawings. The rod 36 is provided with spaces or depressions 37 either of which being adapted to receive the locking 65 element 34 to sustain the rod rigidly upon

the member 31. The rod 36 has both of its ends provided with openings 38, and through one of these openings is adapted to connect with the hook 20, while the opposite opening is received by a similar hook 39 70 which is provided upon the lower step of the ladder when the device is in the position illustrated in Fig. 2. The rod, it will thus be seen, provides a brace when the device is set up to form a ladder and also provides a support for the member 27 when the device is in the position illustrated in Fig. 3 of the drawings. The inner connecting strip 28 of the member 27 or the strip or connection of the said member with the rod or shaft 23 has its inner edge beveled or inclined to correspond with the inclination of the board but when the device is set up to provide a ladder as illustrated in Fig. 2. By providing the side arms 26 of the member 27 with the elongated slots the openings 25 it will be noted that the said member 27 may be swung to have its inner slit firmly engage with the outer face of the board, and whereby an additional support is provided between the board and the ladder. It is also to be noted that the connecting strips for the member 27 are secured to only one of the edges of the arm 26 which permits of the said member 27 being swung to have 90 its side arms arranged adjacent the side members of the legs of the ladder and this strip directly over the edges of the said arms or legs, so that the member 27 occupies one of the comparatively small steps 95 which will in no wise interfere with the folding or clasping of the device to the position illustrated in Fig. 1 of the drawings.

Disposed approximately central of the 105 ladder and passing through openings provided in the side arms or the legs thereof is a rod or shaft 40 which extends a suitable distance beyond said sides of the ladder and which provides trunnions or bearings for 110 substantially rectangular elements 41. These elements 41 have both of their ends formed with elongated slots 42, and arranged within the oppositely disposed slots one of the ends of the said members is what I term a combined wringer support, and drain board 43. The member 43 is substantially L-shaped in cross section and is removably retained within the slots 42 through the medium of pivoted catch or hooks 44 provided upon the elements 41. By this arrangement it will be noted that the member 43 is removable as well as reversible so that the water from the wringer may be delivered by the drain board of the device to 115 either side of the elements 41 when the said elements provide the central legs for the tub stand when the device is in the position illustrated in Fig. 4 of the drawings. The leg members 41 have suitable openings 45 120 130

which are adapted to receive the sliding bolts 18 of the board 1 to rigidly sustain the legs in their proper position when the device is set up to provide the tub stand. When 5 in this position it will be noted that the board 1 is arranged at an angle between the side arms of the member 27 as well as between the elements 41. The latter has pivotally connected to its lower side members 10 on the ladder and adjacent the lower portion of the said ladder is substantially rectangular frame 46, said frame including a connecting member 47 for its side arms, the said connecting member being centrally provided with depression 48 which is adapted 15 to receive rounded front end of the board 1 when in the position illustrated in said Fig. 4. The connecting member 47 is also provided with a suitable eye 48 which is adapted 20 to receive the hook 21 of the board 1.

When the device is set up to provide an ironing board the upper edge of the member 43 is brought into engagement with either of the inclined edges of the cleats 19 of the 25 board 1 as clearly illustrated in the showing of the drawings.

The side members or legs of the ladder are each formed with a depression or cut away portion 49 upon one of their edges, the said 30 depression being sufficient to receive one of the angular members of the element 43, while the second angular member is adapted to pass between the side members of the ladder, when the device is in its folded position. 35 When in such position the frame 46 is folded between the side members of the ladder, the board 1 is swung over the member 43 to the frame 46; the member 27 is swung upon the opposite side of the ladder; the sleeve 40 board has its T-shaped portion arranged between the spaces of the ladder, while the rod 36 is passed over the upper face of the sleeve board, and it will thus be noted that all of the several parts are compactly folded to 45 provide a comparatively small bundle which may be readily stored or transported.

From the above description taken in connection with the drawings, the simplicity and advantages of the device will it is

thought be perfectly apparent to those 50 skilled in the art to which the invention appertains, without further detailed description.

Having thus described the invention, what I claim as new is:—

1. A foldable tub stand, and wringer support comprising a supporting member, end supporting legs pivotally secured at their upper ends to the sides of said supporting member, intermediate supporting legs pivotally secured to and projecting above the sides of said supporting member, a cross bar formed with a socket carried by one of the end supporting legs, an eye on said cross bar, a downwardly inclined brace secured to and 60 between the legs of the other of said end supporting legs, the free end of the brace resting in the socket of the cross bar, a hook connected to the brace for engagement with said eye for retaining the free end of said 65 brace in said recess.

2. A foldable tub stand and wringer support comprising a supporting member, end supporting legs pivotally secured at their upper ends to the sides of said supporting 75 member, intermediate apertured supporting legs pivotally secured to and projecting above the sides of said supporting member, a cross bar formed with a socket carried by one of the end supporting legs, an eye on 80 said cross bar, a downwardly inclined brace pivotally secured to, and between the other of said supporting legs, the free end of the brace resting in the socket of the cross bar, means connected with the brace for engagement with said eye for retaining the free 85 end of the brace in said recess, and means carried by the brace and adapted to be adjusted in the aperture of the intermediate supporting legs for retaining the latter in a 90 vertical upright position.

In testimony whereof I affix my signature in presence of two witnesses.

HUGH D. FORTNER.
